UNITED STATES PATENT OFFICE.

HARRY MCGILLIVRAY, OF NEW YORK, N. Y.

SAFETY DEVICE FOR ELEVATORS.

1,422,774.

Specification of Letters Patent. Patented July 11, 1922.

Application filed March 22, 1921. Serial No. 454,330.

To all whom it may concern:

Be it known that I, HARRY MCGILLIVRAY, a citizen of the United States, and a resident of the city of New York, borough of 5 Manhattan, in the county of New York and State of New York, have invented a new and Improved Safety Device for Elevators, of which the following is a full, clear, and exact description.

This invention relates to safety devices adapted for attachment to elevators and counterweights.

The invention contemplates a means automatically operative to stop an elevator and 15 counterweights in event of the breaking of the cables by which the same are supported.

Another object in view is to provide in connection with a means for automatically stopping and locking an elevator in event 20 of the breaking of the cable, a means for simultaneously cutting off power for driving the same.

A still further object in view resides in the provision of a safety device for elevators which includes pivoted levers having cammed extremities normally retained out 25 of engagement with the guide rails of the shaft by supporting cables for the elevator which cables are connected with the pivoted 30 levers.

A further object of the invention resides in the provision of a safety device including pivoted levers, the cammed extremities of which are provided with guide flanges 35 which function to maintain said extremities in juxtaposition at all times.

A still further object in view resides in the provision of a safety device including pivoted levers with cammed extremities 40 which are adapted to be thrown to active position by means of springs in which means is provided for relieving the springs of wear when the levers are normally retained in in- active position.

Another object is the provision of a safety 45 device of the character described which is simple in construction, inexpensive to manufacture and install and which is thorough- reliable and highly efficient in its purpose.

With the above recited and other objects 50 in view, the invention resides in the novel construction, combination and arrangement of parts set forth in the following specification, pointed out in the appended claims 55 and illustrated in the accompanying drawings, in which;

Figure 1 is a fragmentary front elevation of an elevator and a counterweight therefor equipped with a safety device constructed in accordance with the invention. 60

Figure 2 is a diagrammatic view of the automatic circuit breaking means constituting a part of the invention.

Figure 3 is a fragmentary enlarged front elevation of the upper portion of the car, 65 parts being broken away to disclose the underlying structure and illustrating in dotted and full lines normal and actuated position of the parts.

Figure 4 is a horizontal plan view taken 70 approximately on the line 4—4 of Figure 3.

Figure 5 is a vertical transverse sectional view taken approximately on the line 5—5 of Figure 3.

Figure 6 is a similar sectional view taken 75 approximately on the line 6—6 of Figure 3.

Figure 7 is an enlarged fragmentary elevation of the counterweight attachment, parts being shown in section.

Figure 8 is a horizontal sectional view 80 therethrough taken approximately on the line 8—8 of Figure 7.

Referring to the drawings by characters of reference, 10 designates an elevator shaft provided with vertical T-shaped guide rails 85

11—11 disposed centrally at the opposite sides thereof over which the car 12 is guided. The car is provided with the usual super- structure which includes the transverse channel iron beams 13—13. The shaft and 90 car may be of any approved type now in general use, the showing made in the drawing being merely illustrative of one form to

which the safety attachment may be applied. The safety attachment comprises 95 a pair of levers 14—14 each of which is pivoted adjacent its outer end as at 15 underneath the outer ends of the beams 13.

The outer extremities of the levers 14 are enlarged as at 16 and said enlarged extremi- 100 ties are provided with cammed outer end walls 17 which are designed to be dis- posed out of contact with the rails 11 when the inner extremities of the levers 14 are

swung upwardly. The inner extremities 105 of the levers are apertured as at 18 for the reception of the vertical bolts 19. The upper ends of the bolts 19 are provided with bifurcated heads 20 in which are re-

ceived the looped terminals 21 of the sup- 110 porting cables 22. The cables 22 are trained over the guide pulleys 23 arranged at the

top of the shaft and the opposite loop terminals 24 of said cables are connected to the counterweight 25 in a manner to be hereinafter set forth. A plate 26 is bolted 5 or otherwise secured to the under side of the channel beams 13 to straddle the same and said plate is provided with spaced apertures 27 through which the bolts 19 extend. A bearing sleeve 28 is arranged over 10 each bolt 19 and is disposed between the inner end of the lever and the under side of the plates 26. The lower end of each bolt 19 has mounted thereon a ball race 29 in which the antifriction balls 30 are retained. A pair of lock nuts 31 are threaded 15 on the lower end of the bolt to retain the ball race 29 thereon. A washer 32 is secured to the under side of the inner end of each lever 14 with its central aperture 20 in alignment with the aperture 18. A coiled contractile spring 33 surrounds each sleeve 28 and bolt 19, the opposite ends thereof respectively bearing on the plate 26 and the upper side of the inner end of the levers 14. 25 The counter weight 25 is provided with a pair of levers 34 each of which are pivoted as at extremities 35 adjacent their enlarged outer extremities 36 to the under side of the transverse beam 37 of the superstructure. 30 The outer end of the levers 34 are cammed as at 38 and are adapted to normally be disposed out of engagement with the guide rails 39 for the counter weight when the inner extremities of the levers 34 are swung upwardly. The locked terminals 24 of the supporting cables 22 are connected to the inner arms of the levers 34 by the bolts 40. A coiled contractile spring 41 is interposed between a plate 42 secured to the beam 37 and 35 a plate 43 secured to the upper side of the extreme inner end of the levers 34. A suitable spacing sleeve 44 is carried by the plate 42 and is arranged within the convolutions of the springs 41 for the purpose of supporting the inner end of the lever 34 prior to the complete compression of the springs 42. The outer enlarged extremities of the levers 14 and 34 are each provided with flanges 45 which extend outwardly from the 40 ends and embrace the guide rails 11 and 39 respectively for maintaining the cammed outer end walls in juxtaposition thereto.

The circuit wire 50 which leads from the source of supply to the controller handle 51 is arranged to traverse the beam 13. The circuit wire 50 is broken at two points 52 and 53 and is provided with spaced terminals 54 and 55 adjacent each of said gaps. A bridge element 56 is provided for each gap 55 or brake 52 and 53. The bridge elements 56 are respectively mounted on a vertically movable rod 58 mounted in suitable guides on the beam 13. The lower extremity of each rod 58 is provided with a roller 59 60 which co-acts with the upper surface of the 65

lever 14. By this arrangement when the levers 14 are swung upwardly to normal position, the bridge element 56 will bridge the gaps and establish communication between the contact terminals 54 and 55. 70

In operation of the device the supporting cables 22 normally support the weight of the car 12 and the counter weight 25 through the bolts 19 and 40 respectively. The upward pull on said bolts will effect contact of the 75 sleeves 28 with the plates 26, the contact of the ball race with the washer 32 and the contact of the inner end of the levers 14 with the sleeves thereby compressing the springs 33. At the same time the inner end of the 80 levers 34 of the counter weight will be held in contact with the spacer sleeves 44. The length of the sleeves 28 and 44 being sufficient to prevent the entire compression of the springs 33 and 41. The anti-friction 85 balls 30 will permit the bolts 19 to rotate whereby to relieve the cable of any kinks or twist which may occur therein.

In this position the outer cammed extremities or walls 17 and 38 of the levers 14 90 and 34 will be maintained out of contact with the guide rails 11 and 39. In event of the breaking of all of the supporting cables 22, the springs 33 and 41 will be instantly released to effect a downward movement of 95 the inner ends of the levers 14, and 34 respectively the rods 58 will gravitate to break the circuit wire 50 by opening the gaps 52 and 53 upon movement of the bridge elements 56 out of contact with the terminal 100 contacts 54 and 55. This will automatically cut off the power. In event of the breaking of one of the cables only, the downward movement of one of the levers 14 will break the circuit wire 50 to cut off the power without jamming the car so that repairs can be made before the other cable is severed. 105

While there has been illustrated and described a preferred embodiment of the invention, no limitation is necessarily made to the precise structural details therein exhibited as it is to be understood that variations and modifications that properly fall within the scope of the appended claims may be resorted to when found expedient. 110 115

I claim:

1. The combination with an elevator shaft having vertical guide rails, a car, a plurality of supporting cables therefor, independent means carried by the car and attached to 120 each supporting cable adapted to coact with the guide rails for frictionally locking the car within the shaft upon breaking of the supporting cables and a circuit adapted when closed to operate the car, of circuit breakers 125 normally held in circuit closing relation by the levers for completing the circuit and operable by movement of said levers upon breaking of any of the cables to open the circuit for stopping the car. 130

2. In a safety device for elevators, the combination with an elevator car and counterweight therefor movable between vertical guide rails, of means for frictionally locking the car and the counterweight within the shaft comprising a pair of levers carried respectively by the car and the counterweight, each of said levers including a cammed head, means for rocking the levers to effect frictional engagement of the same with the guide rails, and a pair of cables constituting a connection between each car lever and counterweight lever for holding the levers normally in an inactive position to retain the cams out of engagement with the guide rails, in combination with a circuit serving when closed to operate the car and including an operating controller switch, a pair of circuit breakers, each normally held in circuit closing relation by one of the car levers and operable upon breaking of the cables to open the circuit for stopping the car.
3. In a safety device for elevators, the combination with an elevator car and counterweights therefor movable between vertical guide rails in the elevator shaft, of means for frictionally locking the car and counterweights within the shaft in event of breaking of the cables, comprising levers pivoted respectively to the car and counterweight, each of said levers including cammed heads, a spring adapted to coat therewith for rocking the lever to a position to effect frictional engagement of the cammed head with the guide rail, a cable connection between each set of car and counterweight levers for holding the levers normally inactive to retain the cammed heads out of engagement with the guide rails, and means interposed between the lever and the car or counterweight structure constituting the abutments for limiting the compression of the springs whereby the carrying load is carried by said means.
4. In a safety device for elevators, the combination with an elevator car and counterweights therefor movable between vertical guide rails in the elevator shaft, of means for frictionally locking the car and counterweights within the shaft upon breaking of the cables, comprising a plurality of levers pivoted respectively to the car and counter-
- weights, a cammed head on each of said levers having side flanges projecting outwardly therefrom to retain the same in juxtaposition to the guide rail, a spring adapted to coat therewith for rocking the lever to effect frictional engagement of the same with the guide rail, cables respectively attached at their opposite ends to one of the levers of the car and one of the levers of the counterweight for connecting the same and for holding the levers normally inactive to retain the cammed heads out of engagement with the guide rails, and means coacting with each lever of the car for throwing off the power to bring the car to a stop in event of breaking of its cable.
5. In a safety device for elevators, the combination with an elevator car and counterweights therefor movable between vertical guide rails in the elevator shaft, of means for frictionally locking the car and counterweights within the shaft upon breaking of the cables, comprising a plurality of levers pivoted respectively to the car and counterweights, a cammed head on each of said levers having side flanges projecting outwardly therefrom to retain the same in juxtaposition to the guide rail, a spring adapted to coat therewith for rocking the lever to effect frictional engagement of the same with the guide rail, cables respectively attached at their opposite ends to one of the levers of the car and one of the levers of the counterweight for connecting the same and for holding the levers normally inactive to retain the cammed heads out of engagement with the guide rails, and means coacting with each lever of the car for throwing off the power to bring the car to a stop in event of breaking of its cable, said means comprising in the operating circuit of the car a plurality of gaps corresponding to the number of levers, a movable rod having a bridge member carried thereby, said rod having engagement with the lever for normally holding the bridge member carried thereby, said rod having engagement with the lever for normally holding the bridge member in bridging relation to the gap when the lever is in normal position.

HARRY MCGILLIVRAY.
